SECTION FOR A TELESCOPING CRANE BOOM

Russell L. Stern, Greencastle, Pa., assignor to Walter
Kidde & Company, Inc., Clifton, N.J.

Filed June 25, 1971, Ser. No. 157,074

Term of patent 14 years

Int. Cl. D15—04

U.S. Cl. D41—1

FIG 1

FIG 2

FIG. 3

FIG. 4

FIG. 5

FIG. 6

FIG. 1 is a perspective view of a section for a telescoping crane boom showing my new design, the view showing the front, bottom and one side thereof;

FIG. 2 is a side elevational view, on a reduced scale, showing the opposite side thereof;

FIG. 3 is a top plan view thereof;

FIG. 4 is a bottom view thereof;

FIG. 5 is a front elevational view thereof on an enlarged scale; and

FIG. 6 is a rear elevational view thereof on an enlarged scale.

I claim:

The ornamental design for a section for a telescoping crane boom, substantially as shown.
